UNITED STATES PATENT OFFICE.

ARTHUR P. MILLER, OF MOUNT CLEMENS, MICHIGAN.

RUBBING-BOARD.

1,084,467.

Specification of Letters Patent. Patented Jan. 13, 1914.

Application filed April 5, 1912. Serial No. 688,723.

To all whom it may concern:

Be it known that I, ARTHUR P. MILLER, a citizen of the United States, residing at Mount Clemens, in the county of Macomb and State of Michigan, have invented new and useful Improvements in Rubbing-Boards, of which the following is a specification.

This invention relates to rubbing boards, and has for its object to provide a rubbing board with a soap pocket which, taken in connection with a detachable grate, a follower, and means for operating the follower, enables a cake of soap to be confined within the body of the rubbing board, and to be fed forward as required, thus enabling the operation of washing clothing to be carried on, without the necessity of handling the soap.

With the above and other objects in view, the invention consists in the construction, combination and arrangement of parts, as will be hereinafter more fully described, illustrated in the accompanying drawings, and pointed out in the claim hereunto appended.

In the drawings: Figure 1 is a front elevation of the rubbing board, embodying the present invention. Fig. 2 is a rear elevation thereof. Fig. 3 is a vertical cross section taken through the soap pocket. Fig. 4 is a horizontal section through the same.

Referring to the drawings, 1 designates an ordinary wash-board or rubbing board, which, in carrying out the present invention, is provided at a suitable point with a pocket 2 adapted to contain a cake of soap. At the front this pocket is covered by a removable grate, embodying a substantially rectangular grate frame 3, and cross bars 4, which pass through rearwardly extending flanges 5 at the back of the grate frame, said grate bars being extended to form tongues 6 which are insertible in and removable from holes 7 in the wash-board at one side of the pocket, enabling the grate to be detached from the wash-board to insert another cake of soap.

At their opposite ends, the grate bars are extended beyond the margin of the grate and bent over to form a spring hook or clasp 8 adapted to embrace and grasp the side bar 9 of the frame of the rubbing board,

said clasp being provided with a laterally extending finger grip 10 formed by bending the wire upon itself, as clearly illustrated in the drawings. The side bar 9 is shown as provided with a notch or recess 11, into which the clasp is adapted to fit when the grate is in its applied position.

Arranged back of the pocket 2 is a fol- 60 lower board 12, provided on its front face with a block 13 adapted to work into and out of the soap pocket, the object being to force the cake of soap forwardly against the grate bars, where it will be subjected to the rubbing action of the clothes, as they are moved over the face of the rubbing board. The follower block is urged forward by means of a cam roller 14 having the shaft 15 thereof journaled in flanges 16, extending back from 70 the rear of the board and connected to the cap 17 of the board, in order to more effectively brace the same. One end of the shaft is extended and provided with an operating handle 18, and this handle is provided with 75 ratchet teeth 19 adapted to be engaged by a pawl or detent 20 pivotally mounted, at 21. It will now be observed that by turning the cam roller, the follower board may be pressed toward the front of the rubbing 80 board, thereby advancing the cake of soap and pressing the same firmly against the grate bars, where it may be reached by the clothes, as the latter are rubbed along the corrugated face of the board. 85

Below the plane of the soap pocket, there is arranged a drain trough 22 divided from the pocket by a shelf 23, forming the bottom of the soap pocket, said shelf being provided with drain grooves 24 in its rear edge, as 90 shown. The rear wall of the pocket is also cut away, as shown at 25, to give access to the board 12. It will also be observed that any surplus water getting into the main soap pocket will drain therefrom through 95 the back of the board, and return through the trough 22 to the tub.

What is claimed is:

A rubbing board provided with a soap pocket extending through the same from 100 front to back, a detachable grate covering the front of the pocket, a follower adapted to press a cake of soap toward the grate, and means for forcing the follower forward, the

grate embodying an open center frame, an inwardly extending flange, and grate bars extending through said flange across the open center of the grate frame and projecting beyond one side thereof into openings in the board, said bars projecting also beyond the opposite side of the grate frame where they are bent to form a spring clasp which

engages the board to retain the grate in place.

In testimony whereof I affix my signature in presence of two witnesses.

ARTHUR P. MILLER.
